UNITED STATES PATENT OFFICE.

CHARLES JACOB ZIGLER AND WILLIAM POOL HOLDEN, OF CHICAGO, ILLINOIS.

ELECTRIC SWITCH.

1,190,359.

Specification of Letters Patent. Patented July 11, 1916.

Original application filed August 27, 1913, Serial No. 786,860. Divided and this application filed February 14, 1914. Serial No. 818,636.

To all whom it may concern:

Be it known that we, CHARLES JACOB ZIGLER and WILLIAM POOL HOLDEN, citizens of the United States, residing at Chicago, in the county of Cook and State of Illinois, have invented certain new and useful Improvements in Electric Switches, of which the following is a specification.

This application is a division of our former application for electric switches, filed August 27, 1913, Serial No. 786,860, which application describes the general construction of an improved safety switch embodying our invention.

15 The present invention relates more particularly to the contact members, and to the method of attaching or mounting the same.

Among the objects of this invention are to provide a switch structure having the contacts mounted so that they are not apt to get out of alinement; to provide contacts which may be adjusted for wear; to arrange the parts so as to make as quick break as possible without the use of springs; and in 25 general to improve the construction of such devices and cheapen the cost thereof.

In the accompanying drawings illustrating this invention: Figure 1 is a front view of a switch with the cover removed from 30 the box; Fig. 2 is a sectional view of the same; and, Figs. 3 and 4 are details of the stationary contact members.

While our switch members may be arranged in various ways, we have shown them 35 in these drawings mounted in a box 5, which is provided with partitions or supports 6 and 7, preferably made of insulating material. These supports are each provided with one or more contacts 8 and 9, those 40 on one support being arranged in alinement with corresponding ones on the opposite support. These contacts are of the particular improved form shown in detail in Figs. 3 and 4, and comprise base portions 10, by 45 means of which they are secured to the plates, and outwardly extending yielding contact portions 11. The latter are substantially L-shaped with the contact portion 12, substantially parallel with the base 10. An 50 adjusting screw 13 passes through the contact members 11, one of such members being tapped to receive the threaded portion thereof, and is provided with a locking nut 14. By means of this adjusting screw the blades 55 may be drawn together to take up any wear.

The movable contact members 15 are of the novel form clearly shown in Figs. 1 and 2 and comprise flat blades with their ends given quarter turns so as to bring the contact portions at substantially right angles 60 to the flat central portion. These blades are mounted on a cylinder 16 which is preferably made of wood or other suitable insulating material and is slotted as indicated at 17 to receive the flat central portion of 65 the blades, which portions fit closely in such slots, and are thereby held in proper alinement. The blades are fastened in such position by means of screws or the like 18. The cylinder 16 is pivotally mounted midway between the upper and lower stationary contacts, and is provided with a handle 19 for turning the same. The contact portion 70 12 of the stationary contact members are arranged so that they are substantially at right angles to the ends of the blades 15, which permits the blades to pass in between the outer or free ends of these contact portions. This permits the stationary contact 75 blades to be made of relatively heavy material, and yet gives a flexible yielding contact. The method of mounting the blades 80 15 in the cylinder 16 makes a very effective and substantial support for such blades and provides an exceedingly cheap form of construction. Furthermore, the twisting of the ends of the blades tends to stiffen the contact portion thereof and to hold them in proper alinement. It will also be noted 85 that on account of these blades being mounted on a rotary support between the upper and lower contact members, there is little or no twisting strain on the blades and the strains due to opening and closing the switch 90 are more or less evenly divided.

Having thus described our invention, which however, we do not wish to limit to the exact construction shown and described, except as specified in the following claims, what we claim and desire to secure by Letters Patent is:

1. A switch member for an electric switch comprising a roller having transverse grooves therein, and contact blades secured in the bottoms of said grooves, lying in a 105 plane passing substantially through the axis of the roller, the ends of said blades being given a quarter turn so that they will stand in planes at right angles to the axis of the roller.

2. A switch member comprising a rotatable support having a slot in the side thereof, a contact blade secured in the bottom of said slot with its ends extending some 5 distance beyond the support, each end of said blade being given a quarter turn so that it will stand in a plane at right angles to the axis of the support to form contacts.
3. A rotatable cylinder formed of insulating material and having a transverse slot 10

therein, a blade having a flat central portion fitting closely in said slot, the ends of said blade being turned 90° to form engaging portions, and means for securing the blade in the slot.

CHARLEY JACOB ZIGLER.
WILLIAM POOL HOLDEN.
